UNITED STATES PATENT OFFICE.

WILLIAM A. LAW, OF ST. PAUL, MINNESOTA.

HAY-CARRIER.

SPECIFICATION forming part of Letters Patent No. 767,574, dated August 16, 1904.

Application filed October 27, 1903. Serial No. 178,756. (No model.)

To all whom it may concern:

Be it known that I, WILLIAM A. LAW, a citizen of the United States, residing at St. Paul, in the county of Ramsey and State of Minnesota, have invented a new and useful Hay-Carrier, of which the following is a specification.

This invention relates to certain new and useful improvements in hay-carriers and tracks for the same.

10 My invention relates particularly and primarily to that class of hay-carriers in which a car or carriage movable upon a track is provided with a swiveled body carrying rope guides or pulleys over which the hoisting-rope is reeved, said hoisting-rope carrying a pair of sheaves provided with means for the attachment thereto of the ends of a sling or device for carrying the load.

Among the objects of my invention are an 20 improved construction of the body of the device, which I shall describe as the "carrier," whereby the pulleys are disposed at right angles to each other in order to enable the load to enter the door of the barn or mow 25 lengthwise and to reverse to the extent of a one-quarter turn after having entered, thus spreading the load in the barn or mow, and consequently causing the load to require less manual handling than would otherwise be the 30 case.

Another object of my invention is by the improved construction of the carrier to enable the load to be hoisted into the barn through a door disposed at right angles to the 35 track, which latter usually extends through the barn, under the peak or gable of the same, from one end to the other. This enables my improved carrier to be successfully utilized where the principal entrance to the barn is a 40 side door.

With these and other objects in view, which will readily appear as the nature of my invention is better understood, said invention consists in the improved construction, arrangement, and combination of parts, which will be 45 hereinafter fully described, and particularly pointed out in the claims.

In the accompanying drawings, Figure 1 is a perspective view showing my improved hay-

carrier mounted upon a track in position for 50 operation. Fig. 2 is a side elevation, partly in section, of the carrier. Fig. 3 is an end view of the same. Fig. 4 is a sectional detail view taken through the track, the carrier, and the locking device, whereby the carrier 55 is temporarily retained in position at a certain point upon the track. Fig. 5 is a sectional detail view taken on the line 5 5 in Fig. 2. Fig. 6 is a transverse sectional detail view of the track. Figs. 7, 8, and 9 are 60 detail views illustrating the track construction at the point where two sections of track are connected. Fig. 10 is a detail view of a special rivet employed for uniting the side members of the track. Fig. 11 is a perspective detail view of one of the track-hangers.

Corresponding parts in the several figures are indicated by similar numerals of reference.

The track 1 of my improved device is composed of two angle-bars 2 2 shaped in cross-section and designated 2 2. These side members are connected at intervals by means of special rivets 3, one of which has been illustrated in Fig. 10 and which consist each of a spacing bar or member 4, having upturned ends 5, at 70 the ends of which are cross-pieces 6, which constitute the rivets. It will be seen that when the spacing bars or members 4, with the upturned ends 5, are introduced between the angle-irons 2 2, which have been previously 75 drilled for the reception of the rivet members 6, the latter may be readily clenched, so as to firmly connect the angle-bars 2, forming the side members of the track, which said side members at the same time are properly and 80 evenly spaced apart. Two of the side members 2 2 thus connected form a track-section, any number of which may be employed to make up the track, according to the length 85 of the latter. These track-sections are connected by means of washer-plates 7, inserted from the top and provided at their lower edges with recesses 8 to admit the members 5 of the adjacent rivets 3. The washer member 7 is further provided with lateral extensions 8', forming abutments for the opposing 90 ends of the track-sections. Underneath the latter I place a flanged truss-plate 10, having

lateral extensions 11, filling the space between the ends of the horizontal flanges of the angle-plates constituting the track. The truss-plate 10, as well as the washer-plate 7, is vertically perforated, as seen, respectively, at 12 and 13, for the admission of a vertical bolt 14, which being properly inserted and secured by means of a nut serves to hold the ends of adjacent track-sections securely in position with relation to each other. This, it will be seen, is practically a track construction which prevents the ends of adjacent track-sections from sagging and enables it to be easily supported in a level position, which, as will be readily understood, is essential to the successful operation of the invention.

The means for suspending the track consist of hangers 15, provided at their lower ends with oppositely-disposed shoulders 16, from which depend the supporting members 17, having T-heads 18 at their lower ends. The supporting members are in practice introduced between the two side members 2 of the track, the T-heads 18 forming the supporting means for the latter, while the shoulders 16 rest upon and engage the horizontal upper edges of the vertical members of the angle-bars 2. It will be noticed that by this simple means the track may be readily supported in a horizontal position, any desired number of hangers being employed, the hangers being suspended in any suitable manner under the roof of the barn or structure in which the device is to be employed.

It will be seen that by the track construction just described an unbroken length of double track is provided by the horizontal members of the angle-irons 2, which constitute the side members of the track.

The car 19 of my improved device is provided with four or more supporting-wheels 20, which are of the usual flanged construction and adapted to engage the track. The car is preferably composed of two separate parts 21 21, connected by bolts 22 and combining to form a ring 23, which is supported below the track. The side members 21 of the car are suitably spaced apart by the side members of the ring 23, and suitably-disposed braces 24 are provided to extend under the track and to prevent the car from jumping the track. The ring 23 serves as a swivel to support the body of the carrier, and it is in order to enable the said ring to be properly connected with the carrier that the car or superstructure is preferably made in two separate pieces, as herein described.

The carrier 25 is composed of a crown piece or casting which comprises a flanged ring 26, provided with inwardly-extending lugs 27, 28, and 28^a. This crown-piece or flanged ring is engaged by the ring 23 of the superstructure and has a swiveling connection with the latter, as will be readily understood. Suitably bolted to the under side of the lug 27 is a pul-

ley-frame 29, and to the under sides of the lugs 28 28^a is bolted another pulley-frame, 30, which is disposed at right angles to the frame 29. The latter carries a pulley 31, which is disposed a trifle above and at approximately right angles to a pulley 32, journaled in the frame 30. The flanged ring 26 and the frames 29 30, which are firmly bolted together, constitute the main structure of my improved carrier. The lug 28^a at one end is provided with a projection 34, which co-operates with the oppositely-located lug 27 to form a guide for the locking device, as will be presently described.

The lower outer or front corner of the bracket 30 is bifurcated, as shown at 35, to form a recess in which an arm 36 is pivotally mounted upon a transverse bolt 37. The diagonally opposite upper corner of the frame is likewise recessed at 38 to afford a bearing for a link 39, which is pivotally mounted upon a bolt 40^a. Pivotally connected with the lower end of the link 39 is a locking member 40, which is composed of two suitably-spaced side members 41, the free ends of which have pivotal connection at 42 with the free end of the arm 36 and co-operate with the latter to form a rope-lock, the pivotal point 42 being disposed near the lower edges of the members 41 and 36, so that when pressed in a downward direction the upper edges of said members will be forced in the direction of each other, thus clamping or biting upon a rope which is passed between the side members or locking-jaws. The link 39 being mounted pivotally at its upper and lower ends, as shown, will act as a toggle to give the necessary freedom of movement to the locking-jaws.

Pivotally mounted between the members 41 of the locking-jaw 40 is an upwardly-extending arm 43, which has a shoulder or offset 44, from which a guide-pin 45 extends upwardly into a socket 46, depending from the upper part of the frame 30 and in which said guide-pin is capable of moving freely. A spring 47, coiled upon the guide-pin 45 between the shoulder 44 and a washer 48, disposed against the under side of the socket 46, serves to force the arm 43, and with it the inner end of the locking member 40, in a downward direction, so as to co-operate with the member 36, as already described, to bite upon the rope passing between the locking members. The arm 43, however, is extended upwardly through the swiveled ring 27 and terminates in a frame 49, which normally occupies a position transverse to the track and underneath the latter.

The track carries at the point where the load is to be elevated a trip-block 50, which in its preferred construction is provided at its ends with two inclined planes 51, each terminating abruptly in a shoulder or depression 52. The trip-block itself is curved on its under side, and it is provided with upwardly-extending hangers 53, which are perforated for

the passage of bolts 54, which are fitted with nuts and washers, whereby the trip-block is secured firmly in position. The frame 49 of the arm 43, which is intended and adapted to engage the trip-block, is beveled, as shown at 55, upon the under side of its upper cross-bar, so that in the natural course of operation it will readily pass into engagement with the trip-block.

10 The frame 49 of the trip-arm 43 is permitted to move freely in a vertical direction, but prevented from swinging or oscillating by the guides formed by the lug 27 and the extension 34 of the lug 28^a, which have been 15 already referred to.

A pair of sheaves 56 and 57 are provided, the frames of said sheaves or blocks being provided in the usual manner with hooks 58, to which the sling or other means for attaching the load may be connected. In the example shown in the drawings the hoisting-rope 59 is made fast to the sheave 57, is reeved from thence over the pulley 31, thence down under the pulley in the sheave 56, thence under the pulley in the sheave 57, thence upward through the rope-lock, composed of the members 36 and 40 and coöperating parts, thence over the pulley 32, and to the point where the draft is applied. In operation when 30 the car starts in the direction of the trip-block, which is mounted in proximity to the door of the barn, the trip-block will at the proper time engage under the frame 49, thus elevating such arm and causing it to be retained in an elevated position by the beveled portion of the frame 49 dropping into the proximate recess 52 of the trip-block. The car is thus retained in a stationary position and the rope-lock is opened, so as to admit 35 of the free passage of the hoisting-rope. Draft upon the latter being relaxed, the hoisting pulleys or sheaves 56 57 will descend by their own weight until a load may be attached thereto. Draft being now applied to 40 the hoisting-rope, the load will be elevated. The sheave 57, which is directly influenced by the hoisting-rope, will rise ahead of the sheave 56 and will presently strike against the under side of the pivotally-connected members 36 45 and 40. This will cause the jointed ends of said members to move upwardly, thus lifting the frame 49 of the arm 53 free of engagement with the trip-block, and the draft being obviously continued the car will pass out of 50 engagement with said trip-block. At the instant it leaves, however, the tension of the spring 47 will force the arms 43 in a downward direction, thus causing the lock to bite upon the hoisting-rope, thus sustaining the 55 load in an elevated position, it being obvious that the heavier the load the more firmly will the lock engage the hoisting-rope. It is true that the draft applied to the hoisting-rope for the purpose of moving the carrier along the 60 track will have a lifting action tending to re-

lease the rope from the lock; but as soon as the draft ceases the action of the spring 47 will again cause the rope to be engaged by the locking device and the load will be held suspended, as will be readily understood. The 70 load is dropped at the proper point by ordinary tripping mechanism, which is no part of my present invention.

By the improved construction of the carrier, which has been herein described, the 75 hoisting-sheaves may be so connected with the load that the latter shall be presented end first to the door or opening in the barn in which it is to be deposited, said load being capable of swinging after entering the barn, 80 so as to be placed sidewise in the latter, thereby enabling it to be dropped to such a position that the least possible amount of manual handling will be incurred after the load has been dropped. It is also obvious that my improved carrier will be extremely useful and desirable when the hay is to be unloaded in a barn or mow provided with a centrally-disposed side door, inasmuch as the load may be carried from the center of the track in either 85 90 direction toward the ends of the barn structure. These and other advantages will be fully appreciated by those familiar with the art to which my invention appertains, and I desire it to be understood that while I have in 95 the foregoing described a simple and preferred construction of my improved haystacker and its related parts I do not thereby limit myself to the precise structural details herein set forth, but reserve the right to any 100 changes, alterations, and modifications which may be resorted to within the scope of my invention and without departing from the spirit or sacrificing the utility of the same.

When, as stated above, the device is used in 105 a barn having a centrally-located side door and the trip-block 50 is consequently disposed opposite to the door, it becomes necessary at times for the carrier to pass by said trip-block in order that hay may be carried to both 110 ends of the barn. This is easily effected by holding the carrier at the quarter-turn while passing the block 50, as will be seen in dotted lines in Fig. 5 of the drawings. The frame 49, forming the upper terminal of the rope-lock-operating arm, being disposed tangentially, as shown, or at a distance from the center of the ring 26 of the carrier, will readily 115 pass by the block 50 and enable the device to be drawn in the direction of either end of the 120 barn or other structure.

Having thus described my invention, I claim—

1. In a device of the class described, a car movable upon a track, a carrier having swivel 125 connection with said car, and two hoisting-pulleys mounted in said carrier, the one at right angles to the other.

2. In a device of the class described, a carrier having swivel connection with a support 130

- ing device, two pulleys journaled in said carrier, one at right angles to the other, a pair of hoisting-sheaves, and a hoisting-rope.
3. In a device of the class described, a car, 5 a carrier-frame having swivel connection with said car, two pulleys journaled in said carrier, one at right angles to the other, hoisting-tackle including a hoisting-rope, a locking device for the passage of said rope, and spring means 10 actuating said locking device upon the cessation of exercise of draft upon the hoisting-rope.
4. In a device of the class described, a carrier comprising a ring, two frames depending 15 from said ring, pulleys journaled in said frames at right angles to each other, links connected pivotally with one of said frames, means having a pivotal connection with the free ends of said links and coöperating with 20 one of said links to constitute a rope-clamp, and spring means to operate said rope-clamp.
5. In a device of the class described, a carrier-frame comprising a swivel-ring having inwardly-extending lugs, depending frames 25 supported by said lugs, hoisting-pulleys journaled in said frames at approximately right angles to each other, one of said pulleys being disposed some distance above the other, links connected with diagonally opposite corners of 30 the frame carrying the lower pulley, means having pivotal connection with the free ends of said links and coöperating with one of said links to constitute a rope-clamp, an arm pivotally connected with and extending upwardly from said connecting means, and spring 35 means to force the said arm and related parts in a downward direction to operate the rope-clamp.
6. In a device of the class described, a car, 40 a carrier-frame having swivel connection with said car, a hoisting-pulley, rope-clamping means disposed adjacent to and slightly below said hoisting-pulley, a hoisting-rope passing through the clamp and over the pulley to the 45 point of attachment of the draft, and means for causing the rope-clamp to close automatically upon the rope, said means including an upwardly-extending arm terminating in a trip-engaging loop located to one side of the center of the swivel-ring of the carrier-frame, whereby, by turning the latter the said loop 50 may be moved past a trip-block upon the track supporting the carrier.
7. In a device of the class described, a carrier, 55 a hoisting-pulley mounted therein, a rope-clamp comprising pivotally-connected members, the free end of one of said members being pivotally connected with the frame, and the free end of the other member being connected pivotally with a link depending from the frame, an upwardly-extending arm having pivotal connection with one of the clamping members, spring means for forcing said arm automatically in a downward direction to 65 operate the rope-clamp, means for engaging 70 said arm to automatically elevate the same at a predetermined point, thereby releasing the rope-clamp, a rope passing through the latter and over the hoisting-pulley, and a sheave upon said rope adapted, when elevated, to engage the under sides of the members constituting the rope-clamp to release the spring-actuated arm.
8. In a device of the class described, a rope-clamp comprising two pivotally-connected 75 members, one of said members having a pivotal support and the other of said members being supported by a link, an arm connected pivotally with and rising from the link-supported member of the clamp, an offset upon 80 said arm, a guide-pin rising from said offset, a socket for said guide-pin, a spring coiled upon the latter to force the arm in a downward direction, a frame at the upper end of said arm, and means to engage said frame, 85 thereby elevating the same against the tension of the spring and opening the rope-clamp.
9. In a device of the class described, a carrier-frame comprising a swivel-ring and 90 frames depending from said ring, pulleys journaled in said frames at right angles to each other, a rope-clamping device, actuating means for said rope-clamp including a spring-actuated, vertically-movable arm extending 95 upwardly and having a frame at its upper end, and guides for said frame, consisting of lugs formed interiorly upon the swivel-ring.
10. In a device of the class described, a car, 100 a carrier having swivel connection with said car, said carrier including frames and hoisting-pulleys mounted in said frames, approximately at right angles to each other, and one slightly above the other, a rope-clamping device disposed below the lower pulley, a spring- 105 actuated arm pivotally connected with one member of the rope-clamping device and terminating in a frame adapted to be elevated by suitable means at a predetermined point to release the rope-clamp, means for engaging 110 and retaining the arm in such raised position, a pair of hoisting-sheaves, a hoisting-rope made fast to the frame of one of said sheaves, reeved over the upper hoisting-pulley, down under the pulleys of the sheaves and up 115 through the rope-clamp and over the lower hoisting-pulley, one of said sheaves being adapted to engage the under side of the rope-clamp to thereby release the arm of the latter 120 from its supported position and throwing the rope-clamp into operation.
11. In a device of the class described, the combination of the track, a trip-block mounted upon said track and provided with beveled portions forming inclined planes, abrupt recesses at the inner ends of said inclined planes, and a carrier suspended from and having swivel connection with a car traveling upon a track, said carrier having hoisting-pulleys disposed at right angles to each other, and one 130

slightly above the other, a rope-clamp disposed below the lower hoisting-pulley, a spring-actuated arm having pivotal connection with one of the members of the rope-clamp and extended 5 upwardly and terminating in a frame having at its upper end a beveled cross-bar to engage an inclined plane of the trip-block, and hoisting-tackle including a sheave adapted to engage the under side of the rope-clamp to thereby force the spring-actuated arm in an 10

upward direction and out of engagement with the trip-block.

In testimony that I claim the foregoing as my own I have hereto affixed my signature in the presence of two witnesses.

WILLIAM A. LAW.
